UNITED STATES PATENT OFFICE

161,585

HAND TRUCK OR THE LIKE

Peter Victor Lahm, Millersburg, Ohio

Application December 16, 1949, Serial No. 6,673

Term of patent 7 years

(Cl. D14—3)

To all whom it may concern:

Be it known that I, Peter Victor Lahm, a citizen of the United States and resident of Millersburg, in the county of Holmes and State of Ohio, have invented a new, original, and ornamental Design for a Hand Truck or the like, of which the following is a specification, reference being had to the accompanying drawing, forming a part thereof.

In the drawing, Fig. 1 is a front perspective view of a hand truck or the like, showing my new design, and Figs. 2 and 3 are side and top views thereof, respectively.

I claim:

The ornamental design for a hand truck or the like, substantially as shown.

PETER VICTOR LAHM.
